UNITED STATES PATENT OFFICE.

FRANCIS C. COPELAND, OF SAN FRANCISCO, CALIFORNIA.

DESIGN FOR A COMBINED BOOK END, CIGARETTE DISPENSER, AND LIGHTER.

Application filed May 31, 1928. Serial No. 26,920. Term of patent 7 years.

To all whom it may concern:

Be it known that I, FRANCIS C. COPELAND, a citizen of the United States, residing at the city and county of San Francisco, State of California, have invented a new, original, and ornamental Design for a Combined Book End, Cigarette Dispenser, and Lighter, of which the following is a specification, reference being had to the accompanying drawing, forming part thereof.

Figure 1 is a perspective view of my improved combined book-end, cigarette dispenser and lighter, and

Figure 2 is a front end elevation of the design shown in Figure 1.

I claim:

The ornamental design for a combined book-end, cigarette dispenser and lighter, substantially as shown.

FRANCIS C. COPELAND.
